(57) **CLAIM**

The ornamental design for a sole of a golf club head, as shown and described.

DESCRIPTION

FIG. 1 is a perspective view of a sole of a golf club head illustrating the design;

FIG. 2 is a rear elevation view thereof;

FIG. 3 is a bottom plan view thereof;

FIG. 4 is a toe end elevational view thereof;

FIG. 5 is a heel end elevational view thereof; and,

FIG. 6 is a fragmented enlarged detailed view taken from FIG. 1.

The portion of the golf club head shown in phantom does not form any portion of the present invention.
